IGNITER FOR MERCURY-POOL TUBES

Kenneth Joseph Germeshausen, Cambridge, Mass., assignor to Raytheon Manufacturing Company, Newton, Mass., a corporation of Delaware

Application November 23, 1938, Serial No. 241,888

4 Claims. (Cl. 250—27.5)

The present invention relates to mercury-pool tubes, and more particularly to igniters therefor.

Gaseous rectifiers and relay tubes with a mercury-pool cathode possess many advantages over tubes employing a hot cathode. Chief among these are ability to withstand heavy overloads without damage to the cathode, immediate starting without delay for the heating of the cathode, and sturdiness and simplicity of construction.

The main problem in connection with pool-type tubes has been to find a satisfactory method of starting the cathode spot on the mercury pool. Many schemes have been tried. One of these involves interrupting a circuit between the cathode and an auxiliary starting electrode. In combination with this, a holding arc is often employed to maintain the cathode spot, once it has been started, even though the main-anode current falls to zero. Mechanical difficulties, however, attend the moving of an electrode in a vacuum-tight enclosed vessel, and the device does not operate rapidly enough when it is desired to start the arc once each cycle for 60-cycle operation.

A second method, developed by Peter Cooper Hewitt, is with the aid of an external starting band, placed at the mercury meniscus external to the tube. When a high voltage, of the order of 10,000 volts, is impressed on the starting band, the cathode spot is initiated. Though the external starting band has long been used to start Cooper-Hewitt lamps, it has never proven successful with rectifiers or control tubes that must be started millions of times. One objection to the band igniter has been the high starting voltage required, the best tubes requiring from 5,000 to 10,000 volts for ignition.

According to a more recent proposal, a partially conducting electrode is immersed in the mercury cathode. When a current of sufficient magnitude is passed between the starting electrode and the mercury pool, the arc is initiated. Ignitrons, as tubes employing this system are called, require rather large amounts of current and power to start the cathode spot. A typical igniter requires about 15 amperes at 75 volts for successful operation. As it is necessary, furthermore, that the current through the igniter be in one direction only, a rectifier tube is required to be connected in series with the igniter; and since the currents are large, the rectifier must be both large and somewhat expensive. The applications of ignitrons have consequently been sharply limited, so that they are now used mainly in large-resistance welders to control the duration of the weld.

Each of the above methods, therefore, has cer-

tain inherent disadvantages which it is an object of the present invention to overcome.

A further object contemplates the provision of a device of the above-described character that shall overcome the necessity for employing high starting voltages, such as are employed in the band-starter type of tube, and shall at the same time overcome the necessity for using large currents as are employed in the ignitron type of tube. According to the present invention, therefore, it is possible to employ low starting voltages accompanied by low currents, thus obtaining the advantages of both the band-starter and the ignitron types of tubes, without their disadvantages.

Other and further objects will be explained hereinafter, and will be particularly pointed out in the appended claims.

The invention will now be explained more fully in connection with the accompanying drawing, in which Fig. 1 is a fragmentary view illustrating starting electrodes as separated from a mercury-pool cathode by an exceedingly thin insulating layer; and also illustrating a slanting disposition of starting electrodes; Fig. 2 is a cross section of the modification shown in Fig. 5; Figs. 3 and 4 are similar sections of modifications; and Fig. 5 is a view similar to Fig. 1 of a modification. Dimensions that have been found to work, in practice, were as follows: for an anode current of 1 ampere, the maximum cross-sectional area of the igniter was not more than about .09 square inch, and the maximum cross-sectional dimension not more than .3 inch. With increase in anode current, the dimensions of the starter may be increased. In general, the maximum cross-sectional dimensions must be determined by experiment, and may depend on the current rating of the tube. The starter for a particular tube may be small enough to enable the arc and cathode spot to keep the tube free from mercury that might otherwise stick to it.

The starting voltage required may be reduced by bearing in mind that it depends upon the voltage gradient produced at the mercury surface by the voltage applied to the starting electrode and the polarity of the voltage. The voltage gradient for a given voltage applied to the starter will depend on the thickness of the insulation between the starting electrode and the mercury, the dielectric constant of the insulation, and the shape of the mercury surface at the starting electrode. The starting voltage is much lower when the starting band is positive with respect to the mercury cathode.

According to previous practice, where the insulating layer between the starting band and the mercury 30 formed part of the wall of the tube, it was impractical to employ very thin insulating layers because of considerations of mechanical strength. According to a feature of the present invention, on the other hand, the insulating layer may be bonded to and supported by a conducting or semi-conducting member.

It is possible to mount the igniter in the tube in various ways, some of which are illustrated in the drawing. A satisfactory method of preparing an igniter is to take a wire 34 of tungsten, slip over it a close-fitting thin glass tube 36, and then melt the glass down onto the wire, as is done in the making of glass-to-metal seals. The glass used must have a similar coefficient of expansion to that of the tungsten; such glasses are commercially available. Other metals, such as the new sealing alloys, may be used with appropriate glasses. By the above technique, it is possible to produce a thin uniform layer of glass 36 on the tungsten 34, having high electrical and mechanical strength. In practice, layers four to ten thousandths of an inch thick may be used. For clearness, the thickness is shown considerably exaggerated in the drawing.

A wire 34 of .040 inch diameter, coated with a glass layer 36 of five thousandths of an inch thickness, will start a cathode spot when voltages of about 3,000 volts are applied. As the breakdown voltage of the glass layer 36 may be two to three times that value, ample safety factor is provided. The current required to start the cathode spot is negligible, being of the order of a small fraction of a milliampercere.

The wire 34, with the glass tube 36 thereon, may be supported in the mercury pool 30 by a wire support 38, sealed in the wall of the tube 10 at 48, as illustrated in Fig. 1. The glass tube 36 is disposed in the mercury pool 30 so as to insulate the wire 34 therefrom. The free conducting portion 44 of the wire 34 of the igniter assembly is shown exposed inside the tube 10. According to the arrangement shown in Fig. 1, when the cathode spot starts, an arc is drawn between the cathode and the exposed portion 44 of the starting wire 34, which arc aids in the transfer to the anode 5, particularly when the tube is operating at low plate voltages.

The starting voltage is greatly dependent on the shape of the mercury around the starting electrode 34. Slanting the starting electrode with respect to the mercury surface, as illustrated in Fig. 1, will reduce the starting voltage by as much as one-half.

A very effective form of igniter consists of a group of wires 34, as shown in Fig. 2, each wire 34 having its own individual insulating layer 36. The mercury assumes a shape about such groups of wires so that the starting voltage is greatly reduced. The wires may be actually touching, or there may be a small space between them, represented by the distance 54, but the space should not be large enough so that the mercury can freely surround each wire and form a normal meniscus about each. A distance 54 of 0.080 inch has been found to be satisfactory for wires 34 of the dimensions given herein.

Three starting electrodes 34 are shown in Figs. 2, 3 and 5 all supported by the same supporting wire 38.

In Figs. 3, 2 and 5, the three electrodes are shown disposed at the vertices of a triangle. They may, however, be linearly disposed, as illus-

trated in Fig. 4. In Fig. 3, four such electrodes are illustrated. Other numbers of electrodes, and other dispositions, may also be employed.

An igniter assembly slanted with respect to the mercury surface, as illustrated in Fig. 1, is very effective. One or more wires 34 may be employed. The smaller the angle α of slant, the lower the starting voltage will be, but it is desirable that the angle α be at least 30 degrees, so that different levels of mercury may be readily accommodated.

A typical igniter, as shown in Fig. 1, would consist of a wire 34 of .040 inch diameter, coated with a glass layer 36 of five thousandths of an inch thickness, the angle α being 45 degrees. Such an igniter will start a cathode spot when peak voltages of from 800 to 1200 volts are applied to it. Placed in a tube 10 designed to carry two amperes average current, such an igniter has been operated many thousands of hours, starting the arc 60 times per second, without any visible deterioration of the glass on the wires, and without the mercury tending to stick to the glass around the wire, even though the mercury had coated most of the rest of the tube with a sticky dirty layer.

One form of igniter that has worked very well consists of three wires 34 of .025 inch diameter, coated with glass sleeves 36 of .005 to .008 inch thickness and vertically arranged parallel to the axis of the tube supported by the wire 38, as shown in Fig. 5. This form of igniter will start a cathode spot at voltages from 1,000 to 1,500 volts.

It is desirable to apply a considerable excess of voltage to the igniter to insure positive starting. On a starter that nominally requires about 1,500 volts peak for starting, about 2,000 volts of alternating 60-cycle power may be applied, which will give a maximum voltage of about 2,800 volts. During the operation of the tube, the ignition voltage will vary greatly from one ignition to the next. This variation may be great, the range in a typical tube being from 500 to 1,500 volts. The variation seems to be due to the movement of the mercury about the starter, which constantly changes the shape of the mercury.

It has been found that when the voltage applied to the igniter has a steep wave front, such as occurs when the voltage has a peaked wave form, the starting voltage is appreciably lowered.

Hence it would be desirable, in general, that the ignition transformer or ignition circuits provide such a peaked wave.

Further, since the ignition voltage may vary considerably, it would be desirable to use a peaked wave to insure ignition at the same point on the cycle.

Further modifications will occur to persons skilled in the art and all such are considered to fall within the scope and spirit of the invention.

What is claimed is:

1. A tube having a mercury-pool cathode, and a plurality of starting electrodes disposed in the mercury each provided with an insulating layer separating it from the mercury, the distance between adjacent electrodes being small enough to prevent the formation of a normal meniscus about each electrode.

2. A tube having a mercury-pool cathode, and a plurality of starting electrodes disposed in the mercury, contacting the surface of said pool and projecting above said surface, each of said

electrodes being provided with an insulating layer separating it from the mercury, the distance between adjacent electrodes being small enough to prevent the formation of a normal meniscus about each electrode.

3. A tube having a mercury-pool cathode, and a plurality of starting electrodes disposed in the mercury, each provided with an insulating layer separating it from the mercury, the distance between adjacent electrodes being small enough to prevent the formation of a normal meniscus about each electrode, all of said starting electrodes being electrically connected to a common conductor.

4. A tube having a sealed envelope containing a mercury-pool cathode, and a plurality of starting electrodes disposed in the mercury, each provided with an insulating layer separating it from the mercury, the distance between adjacent electrodes being small enough to prevent the formation of a normal meniscus about each electrode, all of said starting electrodes being electrically connected together within said envelope, and a common lead-in conductor for said starting electrodes.
